UNITED STATES PATENT OFFICE.

ALEXANDER G. DONNELLY, OF NEW YORK, N. Y., ASSIGNOR OF ONE-HALF
TO ALDEN SOLMANS, OF SOUTH NORWALK, CONNECTICUT.

SYSTEM OF DEFENDING HARBORS BY SUBMARINE TORPEDOES.

SPECIFICATION forming part of Letters Patent No. 431,565, dated July 8, 1890.

Application filed March 26, 1889. Serial No. 304,875. (No model.)

To all whom it may concern:

Be it known that I, ALEXANDER G. DONNELLY, of New York, in the county of New York and State of New York, have invented 5
a new and useful System of and Apparatus for Defending Harbors by Submarine Torpedoes, of which the following, taken in connection with the accompanying drawings, is a specification.

10 My invention relates to the defense of harbors by submarine torpedoes; and its object is the production of a more efficient torpedo and system of operating the same for harbor defense against naval attack than any now 15 in use.

Modern improvements in ordnance and projectiles make it possible for the fleet of an enemy to take a position in deep water or in such soundings that submarine mines or fixed 20 torpedoes of ordinary construction located on the sea-bottom would have little or no effect on their heavily-armored ships or prevent them from bombarding seaboard cities or towns at long range, and if the mines or fixed 25 torpedoes are attached to booms or anchored so as to float near the surface they are a source of danger to the defense as well as the enemy. In a torpedo the area of effective force is directly as the quantity of explosive 30 force. It follows, therefore, that a torpedo service in deep soundings must be so constructed, arranged, and operated as to enable the operator to bring the explosive energy of the torpedo or torpedoes directly in contact 35 with the hull of the ship or other object to be assailed. The ordinary range of soundings in outer harbors is anywhere from ten to fifty fathoms, and mines laid in even ten fathoms of water in fixed positions on the bottom in 40 order to be effective against heavy armor must contain a charge the volume of which would make it impossible to place them sufficiently close together to prevent the enemy forcing the line, for the reason that if the 45 torpedoes or mines are placed sufficiently near for such purpose in deep soundings the vibrations caused by the explosion of the desired torpedo will almost certainly cause the explosion of the whole line of torpedoes al- 50 most simultaneously, particularly if dynamite is used.

My invention is designed to obviate this objection and render it practical to place the torpedoes sufficiently near together to completely protect the entrance to a harbor and 55 at the same time prevent the vibration resulting from the explosion of any one of said torpedoes firing the remaining torpedoes in the line or series.

My invention consists in certain novel features of construction, arrangement, operation, and combination of parts, which will be readily understood by reference to the description of the drawings and to the claims to be hereinafter given, and in which my invention is 60 clearly pointed out.

Figure 1 of the drawings is a perspective view of the entrance to a harbor, a portion being shown in section and the whole illustrating my invention. Fig. 2 is a sectional 65 elevation of the floating firing-station. Fig. 3 is a sectional elevation of one of the torpedoes with a portion of its chain ladder or flexible anchoring-connection. Figs. 4 and 5 are respectively a plan and a longitudinal section 70 of the upper metal trunnion or guide connected to the flexible lining. Fig. 6 is a longitudinal section of the lower metal trunnion or guide and a portion of the air-tube coupled thereto. Fig. 7 is a side elevation of a short 75 section of the pneumatic tube for connecting the land-station with the floating firing-station, with telegraphic-circuit wires and electric-light wires wound thereon; and Fig. 8 is a similar view of a short section of the pneu- 80 matic tube connecting the air-reservoir on the firing-station with the interior of the inner lining of the torpedo, with the electric-circuit 85 wires for firing the torpedo wound thereon.

In the drawings, A is the land signal-sta- 90 tion, in which is placed an air-compressor a and any suitable electrical apparatus for generating electricity and transmitting messages, said station being made bomb-proof, if desired.

B is the armored floating firing-station, made, 95 preferably, circular in plan or horizontal section, and having its upper portion of considerably larger diameter than its middle or lower section, and having formed therein the ballast-room b, the compressed-air reservoir c, 100 the operating and firing room d, and the gun-room e. The outer edge of the gun-deck is

supported by the inclined annular band of heavy iron or steel *f*, which incloses the annular air-tight chamber *g*. The upper surface of this floating battery and firing-station 5 is curved from the water-line upward toward the center, where there is a hatchway *h*, which is to be closed in rough weather, through which admission is had to the gun-deck by means of the stairway *i*, and directly beneath this 10 hatchway is a hatchway *j* through the gun-deck, through which admission is had to the operating-room *d* by means of the stairway *k*. In the chamber *d* are located as many three-way valves *l* as there are torpedoes in 15 the system, each having an opening communicating with the interior of the reservoir *c*, another communicating with the chamber *d*, and a third extending through the wall of said chamber to the exterior of the vessel, 20 and to which is coupled the flexible pipe *m*, which leads therefrom to a torpedo. In the chamber *d* are also located a telegraphic receiver *n*, connected with the transmitting-instrument *o* in the land signal-station A by 25 suitable circuit-wires *o'* and *o''*, wound upon or carried by the flexible air-pipe *P*, connecting the reservoir *c* with the air-compressor in the signal-station A, as shown in Figs. 1 and 7, and a switch or key-board *p*², connected by 30 suitable circuit-wires *p* and *p'*, wound upon or otherwise connected to and carried by an air-conducting pipe *m* to the explosive in each 35 of the torpedoes in the system, all as shown in Figs. 1 and 8.

35 The floating battery and firing-station is loaded with sufficient ballast to submerge it to the bottom of the gun-deck, as indicated by the dotted water-line in Fig. 2, and is anchored in the desired position by means of a series 40 of chain cables *q* *q*, leading from the outer edge of the gun-deck to any suitable anchors at the bottom of the harbor, as shown in Figs. 1 and 2.

45 The gun-room *e* may be supplied with a battery of heavy ordnance for protecting the torpedo-line or with machine-guns for repelling boarders, the chamber *e* being provided with suitable ports *r*, through which said guns may be fired, and the rooms *d* and *e* may be lighted 50 by electric lights, the electric current for which is conveyed from the signal-station A by means of the circuit wires or cables *s* and *s'*, as shown in Fig. 7.

55 C is one of the torpedoes, composed of an outer barrel-shaped casing *c'*, made, preferably, of steel plates and of sufficient strength to resist the pressure of the water when sunk to the bottom in the deepest soundings where it is likely to be used, and has formed there- 60 in, preferably, at the bilge one or more openings for the admission of water to its interior, said openings, if two are used, being made directly opposite each other, as shown in Fig. 3. To each end or head of this casing is se- 65 cured a metallic cylinder *t*, which is filled with a suitable explosive material—as dynamite or gun-cotton, preferably the latter—to

the center of the mass of which are led the circuit-wires *p* and *p'*, where they are connected by a short piece of platinum wire as a 70 means of firing the explosive in a well-known manner.

75 Within the casing *c'* is placed a flexible air-tight lining *t'* of a shape and size to fit substantially the inner surface of the metal casing *c'* when expanded and capable of collapsing to bring its opposite sides together either along the center of the chamber in said outer casing or pressed against one side of said chamber, according to whether one or two wa- 80 ter-admission openings are made in the casing *c'*.

85 The lining-chamber *t'* has secured to its outer surface at the middle of its length a metal trunnion or guide-rod *u* for each open- 90 ing in the outer casing *c'*, said guide-rod being made triangular in cross-section or pro- 95 vided with wings, the edges of which serve as guides to maintain the lining in proper position, while the spaces between said wings per- 90 mit the free passage of water to the interior of said casing *c'* when the air is exhausted from the lining *t'*, so as to reduce the pressure within said lining below the pressure of the water upon its exterior surface. One of 95 said guide-rods has a tubular center, as shown at *v* in Fig. 6, and has firmly coupled to its outer end one end of the air-pipe *m*, as shown in Figs. 3 and 6.

100 The guide rod or rods *u* have a length at least equal to the diameter of the outer casing *c'*, so that if the water enters in such a manner as to force said flexible lining all to one side of said outer casing neither of said guide-rods will be withdrawn from the open- 105 ing in the outer casing *c'*.

110 The outer casing *c'* is connected at two points *w* and *w'* to one end of a flexible ladder composed of chains *x* *x* and stay-rods *x'* *x'* and made of a length proportioned to the 110 depth of water in which the torpedo is to be sunk, and has its other end firmly anchored to the harbor or sea-bottom in any suitable manner.

115 A series of torpedoes of the kind herein described are anchored, by means of the flexible ladders above described, at suitable distances apart across the mouth of the entrance to the harbor or across the path that must be taken by the enemy to reach a spot from 120 which he could shell the city or fortification that he intends to attack, each connected by a suitable air-conducting pipe with the interior of the compressed-air reservoir *c* and by suitable electric circuit-wires with the fir- 125 ing-room *d*. When an enemy is seen ap- 130 proaching, the party in charge of the shore signal-station immediately telegraphs the fact to the operator on the floating station, with orders to stand ready to receive and execute such orders as may be sent to him. The signal officer at the shore station, by means of a suitable system of co-ordinate angles or transit-lines, determines when the enemy's

ship is approaching or is over any particular torpedo—as one, two, or three—and telegraphs the operator on the floating firing-station to raise said torpedo, which is done by turning 5 the valve *l* belonging to the particular torpedo, when a sufficient quantity of the compressed air in the reservoir *c* rushes through the pipe *m* to the interior of the lining-casing *t*, and, expanding the same, expels the water 10 from the outer casing *c'*, thereby causing it to float and rise as near the surface of the water as the flexible ladder-like cable will permit. If the command comes from the shore station to fire said torpedo, the operator touches the 15 firing-key on the switch or key board, when the explosion instantly takes place; but if the signal officer at the shore station sees that the ship is not in the right position to be damaged by exploding that particular torpedo, 20 but is approaching another torpedo, orders are given to raise the second one and fire it and to sink the first one. The sinking of the torpedo is done by turning the valve *l* so that there shall be a free passage through it from 25 the pipe *m* to the firing-room *d* or into the open air, when the air in the interior of the torpedo will escape into the open air, and the outer casing *c'* of the torpedo *C* will fill with water and sink to the bottom, where it remains 30 ready for use at any future time.

By this arrangement and mode of operating torpedoes I am enabled to use powerful torpedoes and place them much nearer together without danger of exploding more than is required, for the reason of the fact that the torpedoes in their normal positions are on the bottom of the channel in deep water, and when any particular torpedo is required to be exploded it is first brought to the surface 35 or near to the surface of the water, which very materially increases the distance between it and the next nearest torpedo, and those torpedoes that are not to be fired at that time being at the bottom, where the pressure of the water is much greater than at the surface, they are much less liable to be exploded by the vibrations caused by the explosion of the raised torpedo than would be the case if they were at or near the surface of the 40 water and the same distance from the exploded torpedo.

What I claim as new, and desire to secure by Letters Patent of the United States, is—

1. As a means of harbor-defense, the combination of a torpedo, a float carrying said torpedo and comprising a non-collapsible outer casing having an opening for the admission of water thereto and an inner collapsible lining, said torpedo and float being connected to an anchor at the sea-bottom, an armor-clad floating operating-station anchored in a fixed position and containing a reservoir for compressed air or other gases, a land station containing telegraph-instruments and air-compressing or gas-generating mechanism, suitable air or gas conducting pipes connecting said land station with the reservoir 55

on said floating station and said reservoir with the interior of the collapsible lining of the torpedo-float, electric circuit-wires connecting the land station with the floating station and the floating station with the explosive material of the torpedo, an electric switch for controlling the explosion of the torpedo, and an air-valve for controlling the raising and sinking of the torpedo, said valves and switch being carried by the floating station. 70 75

2. As a means of harbor-defense, the combination of a plurality of torpedoes, each provided with a float comprising a non-collapsible outer casing having an opening for the admission of water thereto and an inner collapsible lining and anchored to the sea or river bottom at suitable distances apart across the entrance to the harbor or other place to be defended, an armor-clad floating distributing and operating station anchored in a fixed position and containing a reservoir for compressed air or other gases, a land station containing telegraphic instruments and air-compressing or gas-generating mechanism, suitable pipes connecting said air or gas mechanism with the reservoir of said floating station and said reservoir with the interiors of each of the torpedo-floats, electric circuit-wires connecting said land-station with said floating station and said floating station with the explosive material of each of said torpedoes, a plurality of air or gas valves on said floating station for controlling the raising and sinking of each of said torpedoes, and electric apparatus on said floating station for receiving signals from the land station and for firing any or all of said torpedoes at will. 90 95 100

3. As a means of harbor-defense, the combination of a plurality of torpedoes, each provided with a float comprising a non-collapsible outer casing having an opening for the admission of water thereto and an inner collapsible lining, an observing signal and operating station containing electrical apparatus and air-compressing mechanism, pneumatic pipes connecting said air-compressor with the interiors of the floats of said torpedoes, electric circuit-wires connecting said station with the explosive material in said torpedoes, a series of valves for controlling the flow of air to and from the interiors of said torpedoes, and a suitable electric switch for controlling the firing of said torpedoes. 105 110 115 120

4. A submarine torpedo comprising a main hollow vessel capable of resisting great pressure and provided with an opening or openings into its interior, a flexible and collapsible lining within said vessel, and an air-tube communicating with the interior of said flexible lining, and through which air may be forced into said lining to expand it, and thereby displace the water in the outer casing and cause said torpedo to become buoyant, or through which said air may escape, causing said lining to collapse and the outer vessel to fill with water and cause it to sink to the bottom of the sea, an explosive-filled 125 130

chamber attached to said main hollow vessel, a circuit-wire connecting with the interior of said explosive chamber, and means for exploding said torpedo by electricity.

- 5 5. In a submarine torpedo system, a bomb-proof floating firing-station anchored in a fixed position and containing a compressed-air reservoir, in combination with a torpedo having an outer rigid shell or casing and an 10 inner collapsible lining, air-tubes leading from said air-reservoir to the interior of said lining, valves for controlling the flow of air to

and from said lining, electric circuit-wires leading from said station to the explosive material in said torpedoes, and means of breaking and closing the circuit on said station. 15

In testimony whereof I have signed my name to this specification, in the presence of two subscribing witnesses, on this 7th day of March, A. D. 1889.

ALEXANDER G. DONNELLY.
